DESIGN FOR AN ASH TRAY

Louis A. Revell, Los Angeles, Calif.

Application March 10, 1947, Serial No. 137,488

Term of patent 3½ years

(Cl. D85—2)

To all whom it may concern:

Be it known that I, Louis A. Revell, a citizen of the United States and resident of the city of Los Angeles, county of Los Angeles, State of California, have invented a new, original, and ornamental Design for an Ash Tray, of which the following is a specification, reference being had to the accompanying drawings, forming a part thereof, in which:

Fig. 1 is a top plan view of an ash tray, embodying my new design;

Fig. 2 is a side view;

Fig. 3 is a bottom plan view, and

Fig. 4 is a sectional elevational view.

I claim:

The ornamental design for an ash tray, substantially as shown.

LOUIS A. REVELL.
